UNITED STATES PATENT OFFICE.

ALBERT BROCH, OF ST. LOUIS, MISSOURI.

DESIGN FOR A PUNCH.

SPECIFICATION forming part of Design No. 24,321, dated May 21, 1895.

Application filed February 1, 1895. Serial No. 537,017. Term of patent 14 years.

To all whom it may concern:

Be it known that I, ALBERT BROCH, a citizen of the United States, residing in the city of St. Louis, State of Missouri, have invented and produced a new, useful, and original Design for Punches for Cutting Suction-Plates, of which the following is a specification.

In the accompanying drawings, which form part of this specification, Figure I is a side view of my punch, and Fig. II is a face view thereof.

The rim or edge of the punch projects from the hollow face thereof and is beveled off on the outside as shown.

The leading feature of my design consists in the raised edge whose outline is triangular

in general appearance. Two of the sides of said outline are convex curves of equal length. The third side is below the lower ends of said first mentioned side lines and is shorter than the distance between said ends. The ends of this third side are respectively connected to the ends of the adjacent side lines by short connecting lines located at the lower corners of the triangle.

25

What I claim is—

The design for a punch substantially as herein shown and described.

ALBERT BROCH.
